John Bowes
Letter Patent

9925X

The schedule referred to in these Letter Patent and making part of the same containing a description in the words of the said John Bowes himself of his improvement in making tin, copper and zinc Roofs.

To all to whom these presents shall come. Be it known that I John Bowes of Baltimore in the County of Baltimore and State of Maryland have invented a new and useful machine for making tin, copper and zinc Roofs and that the following is a full and exact description thereof. A. In a bench is placed an iron plate and above that a plate with a groove to receive the edge of the metal which when placed therein by means of a lever which moves up and down turns the edge B. where the sheets are edges by this machine they are placed under another lever or pump and pressed down flat one on the other. There is likewise attached a C. roller on the end of the bench to roll the tin upon as it passes under the pump or lever which makes the roll of metal ready to be laid on the roof. The grooves or edges of the groove roofing being made in a semicircular form instead of an angle as formerly constructed, give the metal a better chance to expand or contract without the danger of cracking, and also forms a gutter to carry off the water and dirt without obstruction. The second advantage derivable from this machine is that the metal is so edged as to prevent its cracking and consequently avoid its susceptibility of rust and is impervious by water. D. The tools to make the circular groove as above stated are made on one side of semicircular form and on the other with a flat edge, so that when the metal is placed between the two it is easily bent without cracking.
